UNITED STATES PATENT OFFICE.

JAQUELIN MARSHALL BRAXTON, OF KEY WEST, FLORIDA,

CONCRETE PILE.

No. 878,765.

Specification of Letters Patent.

Patented Feb. 11, 1908.

Application filed April 9, 1906. Serial No. 310,792.

To all whom it may concern:

Be it known that I, JAQUELIN MARSHALL BRAXTON, a citizen of the United States, residing at Key West, in the county of Monroe, State of Florida, have invented certain new and useful Improvements in Concrete Piles, of which the following is a specification.

The drawing represents a section of a pile with the driving shell applied thereto, and the letter A represents a pile formed of concrete or any desired plastic material and if preferred provided with a reinforcing structure. This pile is preliminarily molded and the metallic driving shoe B attached to the lower end thereof, the top of said shoe being wider or of greater diameter than the pile. Surrounding the pile and spaced therefrom is a metallic driving shell C resting at its lower end upon the top of the shoe and extending at its upper end above the top of the pile where it is provided with a driving head D adapted to receive the impact of the hammer or other pile driving implement used. The force of the blow is transmitted directly from the shell to the shoe and after the driving of the pile the shell is withdrawn. The formation of the shoe of greater width or diameter than the driving shell forms a hole through the earth or other material into which the pile is inserted, of greater diameter than the pile and driving shell which permits the easy withdrawal of said shell after the driving action.

In the operation of the invention the pile is formed and the concrete allowed to set in the usual manner with the shoe attached

thereto. The pile is then introduced into the pile driver leads, and the shell, which is of greater length than the pile and of greater diameter, slipped over the pile so as to rest upon the shoe, when the driving action proceeds in the usual manner. The blow or impact being applied to the head of the shell transmits its force directly to the shoe so that the concrete does not receive any blow and is absolutely protected from injury as the average concrete structure cannot withstand the driving blow necessary to force the pile through rock or other hard material encountered in securing a foundation. After the pile is driven to a proper depth the driving shell is easily withdrawn as the diameter of the top of the shoe provides a clearance space sufficient for this purpose.

Having now described my invention and set forth its merits, what I claim and desire to secure by Letters Patent is:—

A concrete pile provided at one end with a driving shoe having a projection embedded in the pile and a contacting face at the base of said projection extending beyond the sides of the pile, a driving shell spaced from the pile and of greater length, and a head for said shell.

In testimony whereof I have signed my name to this specification in the presence of two subscribing witnesses.

JAQUELIN MARSHALL BRAXTON.
